UNITED STATES PATENT OFFICE.

FRANS H. C. COPPUS, OF WORCESTER, MASSACHUSETTS, ASSIGNOR TO COPPUS ENGINEERING AND EQUIPMENT COMPANY, OF WORCESTER, MASSACHUSETTS, A CORPORATION OF MASSACHUSETTS.

FAN-BLOWER.

1,308,982.

Specification of Letters Patent.

Patented July 8, 1919.

Application filed September 15, 1914. Serial No. 861,907.

To all whom it may concern:

Be it known that I, FRANS H. C. COPPUS, a citizen of the United States, residing at Worcester, in the county of Worcester and 5 Commonwealth of Massachusetts, have invented a new and useful Improvement in Fan-Blowers, of which the following is a specification.

The present invention relates to fan blowers of the type adapted to be used in creating an artificial draft, as, for instance, in maintaining a pressure in the ash pit of a boiler. One of the objects of the invention is to increase the efficiency of devices of this 15 class; the construction and arrangement of parts, by means of which the above and other objects are attained, are set forth in the following description and illustrated in the accompanying drawings, in which—

20 Figure 1 is a side elevation, partly in central longitudinal section, of my improved apparatus, and

Fig. 2 is an end view of the casing or hood for the fan blower, the latter being removed 25 for the sake of clearness.

Similar reference characters refer to similar parts in both figures.

In carrying my invention into effect, I provide a fan 1, of any well known type, disposed within the open end or mouth 2 of a casing or hood 3, which forms a conduit for the air set in motion by the fan. Any well known means may be employed to impart 30 rotation to the fan 1; in the present instance

35 I have shown said fan mounted on the shaft of a steam turbine 4, which is located at a suitable distance from the mouth 2 of the hood 3 to permit the free passage of air to the blades of said fan.

40 It has been the general practice, heretofore, to make the internal diameter of the hood substantially uniform in the vicinity of the fan, with the result that a portion of the air, thrown centrifugally outward by the 45 blades of the fan, impinges against the wall of said hood, in substantially radial directions. As a consequence, a portion of the air leaks backwardly toward the mouth of the hood and, furthermore, there is a considerable pressure loss due to the choking 50 effects and eddy currents caused by the impact of the air against the casing.

My invention contemplates a gradual change in the direction of that portion of

the air thus thrown outwardly, from the 55 initial radial direction imparted thereto by the fan blades, to the desired direction axially of the casing or hood. To this end it is proposed to form the hood or casing, near its mouth, with an inturned annular lip or 60 flange 5 of less diameter than the actual diameter of the hood, and immediately surrounding the fan 1. The forward portions of the blades of said fan project beyond the forward edge of said flange, as shown clearly 65 in Fig. 1. Said flange edge may, if desired, be beveled, as shown at 6, to assist the action of the flange 5 in imparting to the air thrown outwardly by said blades a gradual 70 change in direction before said air comes in contact with the walls of the hood proper. In consequence of the expansion of the hood or casing at the point where the fan is located, the direct radial impingement of the 75 air against the walls of the hood is avoided, and the losses due to the backward leaking of the air, and to the formation of eddy currents, are largely eliminated. A portion of the annular space 7 formed between the 80 walls of the hood 3 and the lip 5 is preferably partitioned off by the walls 8, Fig. 2, to form a passage 9 into which the exhaust steam from the turbine 4 is delivered by means of the pipe 10. The entrance of said steam to the hood 3 in an axial direction 85 further assists in imparting to the air a proper course lengthwise of the hood.

I claim,

1. An air propelling device, comprising a fixed casing having an opening, a rotatable 90 blower having vanes fitting closely in the plane of the opening creating a current of air composed of several components, one a main stream and another a stray stream tending to exert a choking effect between the 95 vanes and the walls of the opening, and means for relieving the choking effect of the stray stream and for directing said stray stream into substantially the same path as the main stream, the casing being constructed to confine the main stream and deflected stray stream in a single path.

2. An air propelling device, comprising a rotatable blower having vanes creating a current of air composed of several components, one a main stream, and another a stray stream issuing in a generally radial direction, a fixed casing surrounding said 105

vanes and fitting closely at the inlet side of the vanes and enlarged toward the outlet side of the vanes to relieve the choking effect of the stray stream on the vanes and to direct said stray stream into substantially the same path as the main stream, and means for confining the two streams thereafter in a single path.

3. An air propelling device, comprising a 10 rotatable blower having vanes constructed to create a current of air having several components angularly related to each other, and a fixed casing of generally cylindrical form surrounding said vanes providing an inlet 15 opening of substantially the same diameter as that of the vanes and providing an outlet of larger diameter, the said vanes extending axially into said enlarged outlet.

4. An air propelling device, comprising a 20 rotatable blower having vanes constructed to create a current of air having several components, one of said components traveling substantially parallel to the axis of rotation of the vanes and the other of said components traveling in a generally radial direction with respect to said axis, and a fixed 25 casing of generally cylindrical contour surrounding said vanes providing an inlet opening of substantially the same diameter as

that of the vanes and providing an outlet 30 of larger diameter, the said vanes extending into said enlarged outlet.

5. In apparatus of the class described, a blower casing of generally cylindrical contour having a mouth of reduced internal 35 diameter, with the interior of said casing expanding to a larger diameter beyond said mouth, and a rotatable blower disposed in said casing, with its vanes closely fitting the mouth thereof, and projecting longitudinally thereof past the point of expansion.

6. In apparatus of the class described, a blower casing of generally cylindrical contour having a mouth of reduced internal 40 diameter, with the interior of said casing expanding to a larger diameter beyond said mouth, and a rotatable blower disposed in said casing, with its vanes closely fitting the mouth thereof, and projecting longitudinally thereof past the point of expansion.

Dated this twelfth day of September, 1914.

FRANS H. C. COPPUS.
